Fig: 1.

UNITED STATES PATENT OFFICE.

BIRDSEILL HOLLY, OF SENECA FALLS, NEW YORK.

CONDENSING STEAM-ENGINES WHICH ARE USED FOR PUMPING.

Specification of Letters Patent No. 14,239, dated February 12, 1856.

To all whom it may concern:

Be it known that I, BIRDSEILL HOLLY, of Seneca Falls, in the county of Seneca and State of New York, have invented a new 5 and useful Improvement in Condensing Steam-Engines to be used for Pumping; and I do hereby declare that the following is a full, clear, and exact description of the same, reference being had to the accompanying drawing, forming part of this 10 specification, in which—

Figure 1, is a vertical section of an engine constructed according to my invention; Fig. 2, a vertical section in the line α, α , of Fig. 1.

15 Similar letters of reference indicate corresponding parts in both figures.

This invention consists in leading the eduction pipe of a steam engine directly into the suction pipe of a common force or lift pump, whereby condensation is effected, and a partial vacuum produced without the cumbersome and expensive apparatus common to condensing engines.

20 The invention is particularly applicable 25 to steam pumps.

In the engine represented in the accompanying drawing both the steam engine proper A, and the pump B, are rotary and constructed according to the Letters Patent 30 which were granted to me on the 6th day of February 1855, not that the invention is limited in its application to engines and pumps of this construction, or to rotary engines and pumps generally but that this 35 affords a good illustration of the invention, and that a pump of this kind having no valves and being continuous in its action is particularly well adapted to the purpose and the entire engine can be very cheaply 40 constructed. The engine and pump are geared together by spur wheels a, b , so that

the former may drive the latter at the desired relative speed.

C, is the suction pipe of the pump and D, the discharge pipe.

45 E, is the induction steam pipe of the engine and F, the eduction pipe which enters some distance into the suction pipe C, and discharges the steam thereinto through a number of small holes c, c , to bring it in 50 contact with the water in thin jets or streams, that it may be quickly condensed.

55 By this mode of condensing the steam we have the advantage of a vacuum condenser without extra expense; and it is obvious that the advantage of condensation in this 60 way, will increase as the height of the column increases in the suction pipe and approaches to thirty three feet. It is also obvious that the difference between leading the exhaust pipes into the suction pipe and 65 leading it into the delivery pipe of the pump would be the difference between exhausting into a vacuum and into a plenum.

65 Therefore what I claim as my invention is—

Leading the eduction steam pipe of a steam engine into the suction pipe of a force or lift pump substantially as herein described whereby the condensation of the steam is effected and a partial vacuum produced without a separate condenser and air pump, and this in engines employed wholly or in part to raise water, without any additional expenditure or loss of power to raise the water to effect condensation.

BIRDSEILL HOLLY.
